(57) **CLAIM**

The ornamental design for rocket toss game, as shown and described.

DESCRIPTION

FIG. 1 is a side perspective view of a projectile of a rocket toss game showing my new design;

FIG. 2 is a side elevation view thereof;

FIG. 3 is a front elevation view thereof;

FIG. 4 is a top plan view thereof;

FIG. 5 is a bottom plan view thereof;

FIG. 6 is a perspective view of a game board of the rocket toss game shown in a closed, folded position;

FIG. 7 is a top plan view of the game board in an open position; and,

FIG. 8 is a bottom plan view of the game board in an open position.

The broken lines in FIGS. 6-8 are for illustrative purposes only and form no part of the claimed design.
